MECHANISM FOR UNWINDING MILL ROLLS

George W. Swift, Jr., Bordentown, N. J., assignor
to George W. Swift, Jr., Inc., Bordentown, N. J.,
a corporation of New Jersey

Application March 20, 1934, Serial No. 716,499

9 Claims. (Cl. 271—2.3)

This invention relates to mechanism for unwinding mill rolls and has for its object to provide an improved construction and arrangement of parts in a device of this character whereby 5 power may be applied to a continuous web for drawing it from a heavy mill roll without unduly affecting the tension under which the continuous web is supplied to other mechanisms which are to operate thereon.

10 One of the objects of my invention is to provide mechanism of improved construction for unwinding mill rolls which while operating on the mill roll through the web, operates to maintain a substantially constant tension in the web supplied 15 thereby to another mechanism.

Another object of my invention is to provide an 20 improved simplified construction for a device of this character which can be economically constructed; which operates directly and effectively 25 upon the continuous web for regulating the tension under which the continuous web is supplied to another mechanism within certain desired 30 limits; and which is immediately responsive to variations in tension in the web.

25 In the embodiment shown on the drawing, my invention contemplates more especially a device of this character suitable for feeding one of the webs of a corrugated paper board machine such as that shown, described and claimed in my co-pending application Serial No. 721,528 which was 30 filed on the 20th day of April, 1934.

35 Certain specific novel features of construction will be described in the specification and recited in the appended claims, reference being had to the accompanying drawing which exemplifies my invention in its adaptation to the corrugated paper board machine shown in my above-identified copending application.

40 Figure 1 is a side elevation of a preferred embodiment of my invention.

Figure 2 is a top plan view of the same, parts being broken away and parts shown in section.

Figure 3 is a central vertical longitudinal section of Figure 2.

45 Figure 4 is a schematic diagram of the power-transmitting connections for upper and lower frictional feed belts and the overspeed web-feeding rolls.

50 A preferred embodiment of my invention is shown on the drawing which illustrates an adaptation of the invention to the unwinding of a continuous liner web from a mill roll for supplying it to a single-faced corrugated web in the manner shown and described in my above-identified copending application.

Referring more particularly to the drawing, a power shaft 1 which may be the side drive shaft of the corrugated paper board machine shown in my above-identified application, carries a sprocket wheel 2 which is connected by a sprocket chain 3 to a sprocket wheel 4 on a counter shaft 5, said counter shaft being journaled in suitable bearings 6 and 7 mounted on a laterally projecting portion 8 of a stationary support or side beam 9 which is spaced laterally from a second stationary support or side beam 10. In the preferred embodiment of my invention, parts 8, 9 and 10 constitute portions of the main longitudinal base frame of the corrugated paper board machine. Keyed to the forward end of the counter shaft 5 is a bevel pinion 11 which meshes with a second bevel pinion 12 journaled in a bearing bracket 13 which is mounted on the portion 8 of the main base frame. The laterally spaced stationary supports or side beams 9 and 10 serve to slidably mount a carriage which has a frame comprising laterally spaced bearing blocks 14 and 15 which are rigidly connected by a plurality of transverse stay shafts 16, 17 and 18, said stay shafts being rigidly secured at their opposite ends to the bearing blocks 14 and 15 by means of cap screws 19. As shown best in Figure 2 of the drawing, the bearing blocks 14 and 15 are provided with bearing bosses 20 for journaling a series of continuously driven transverse live shafts 21, 22 and 23 which carry spaced power-driven web-feeding rolls 24, 25 and 26. As shown best in Figure 3 of the drawing, said web-feeding rolls are journaled upon spaced parallel axes arranged in a common plane. Suitable means for connecting the web-feeding rolls to rotate in unison with each other, may be provided by spur gears 27, 28 and 29 which are respectively keyed to the live shafts 21, 22 and 23. As shown in Figure 2 of the drawing, the bevel pinion 12 is splined to the outer end of shaft 21 by means of a spline 30. Mounted on the stay shafts 16 and 17 are flanged disks 31 and 32 which serve to carry laterally spaced side edge guides or plates 33 for locating the continuous web axially with respect 45 to the web-feeding rolls. Referring now to Figure 3 of the drawing, a continuous web or a liner sheet which is drawn from a mill roll in a manner to be hereinafter referred to, passes over the stay shaft 16 above and part-way around the web-feeding roll 26, thence downwardly under and part-way around the web-feeding roll 25, thence upwardly over and part-way around the web-feeding roll 24, after which said web slides over the stay shaft 17 and under a guide roller 50 55

35 which is freely journaled upon the stay shaft 18. According to the present embodiment of my invention, the continuous web next passes upwardly over one of the arcuate heating units 36 of a curved heating table over which the liner web is drawn preliminarily to being applied to the single-faced corrugated web. Referring again to Figure 2 of the drawing, guide blocks 37 are mounted on the laterally spaced stationary supports or side beams of the main frame for slidably engaging the opposite ends of the bearing blocks 14 and 15 for guiding the transverse sliding movements of the carriage. Mounted on the stationary support or side beam 9 centrally of the carriage, is a bracket arm 38 for journaling an adjusting screw 39 which is threaded into the bearing block 15 and provided with a crank arm 40 by means of which the lateral adjustments may be imparted to the carriage.

20 A schematic diagram of some of the power-transmitting connections shown and described in my above-identified copending application is illustrated in Figure 4 of the drawing, according to which the continuous web 34 is unwound from a mill roll 34^a by the web-feeding rolls 24, 25 and 26 which operate intermittently on the web 34 whenever momentary slight increases in tension in said web draw it into frictional engagement with the rolls so that as the web moves upwardly over the preheating arcuate plates 36, 36, under the action of frictional feed belts 69 and 70 to be presently more fully referred to, it is maintained under a substantially constant tension and velocity during its progressive attachment to the single-faced corrugated web which takes place immediately after the silicate adhesive has been applied to the downwardly presented crowns of the corrugated web. As the liner web 34 is applied to the single-faced web after a preliminary heat treatment as it passes upwardly over the arcuate heating table comprising plates 36, the completely assembled webs move forwardly over the flat heating plates 67 and cooling plate 68 under the action of the upper and lower frictional feed belts. As shown in Figure 4 of the drawing, the upper frictional feed belt 70 travels over a rear follower drum 74 and a front driving drum 83, to the latter of which it is pressed by a guide drum 87. The drum 83 which drives the upper endless feed belt 70, is mounted on a cross shaft 84 and rotated at the same peripheral speed as a drum 91 on a cross shaft 92, said cross shafts 84 and 92 being connected together to rotate in unison by means of intermeshing gears (not shown on the drawing). The lower frictional feed belt 69 is driven by the drum 91 to which it is pressed by a guide drum 94. The frictional feed belts 69 and 70 are driven at a common variable overspeed velocity with respect to the double-faced corrugated board through a variable speed transmission comprising adjustable cone pulleys 100, belt 101, and adjustable cone pulleys 102, the last-mentioned cone pulleys being connected by bevel gears 104, 104, to the common power shaft 1. The driving connections for rotating the web-feeding rolls 24, 25 and 26 are such that the peripheral speed of said rolls is slightly in excess of the substantially constant normal velocity of the liner web 34 as it is applied to the single-faced corrugated web. At the same time, it will be understood that the continuous web 34 in passing from the web-feeding roll 24 to the web-feeding belts 69 and 70, is constrained to move over a path of unchanging length by means

of stay shaft 17, guide roller 35, and arcuate plates 36, 36. In consequence, at each recurring slight increase in tension in the liner web 34, said web is drawn into sufficient frictional engagement with the web-feeding rolls 24, 25 and 26 to enable 5 said rolls to draw on the mill roll for an additional supply of the continuous web. This operation takes place automatically and substantially continuously in such a way that the liner web 34 is maintained under practically constant tension 10 while it is being progressively united to the single-faced corrugated web. It will be understood from the foregoing description that for any pre-established conditions of heat, moisture, and velocity, under which the single-faced corrugated 15 web is supplied, the bottom liner web may be maintained under a substantially constant tension by the automatic operation of the web-feeding rolls 24, 25 and 26, while at the same time the relative tensioning of the several webs 20 composing the double-faced corrugated paper board may be readily effected at will while the machine is running by regulating the variable overspeed velocity of the frictional feed belts which operate on the corrugated board. It will be understood 25 that by watching the condition of the paper boards coming from the machine, any unequalization in the relative tensioning of the several webs resulting in the displacement of one web relatively to another and a tendency to injure or 30 break down the adhesive bond between adjoining webs during an extended drying and curing stage, may be noted at once and immediate steps taken while the machine is running. At the same 35 time, it becomes possible by slight speed adjustments to eliminate all tendencies in the double-faced corrugated paper board to warp or curl.

I claim:—

1. In mechanism of the character described, 40 the combination with a series of spaced power-driven web-feeding rolls the web passing over and under said rolls in succession, means for driving said web-feeding rolls with equal peripheral velocities in excess of the normal speed of said web, side edge guides for retaining said continuous 45 web in predetermined axial position with respect to said rolls, and means for adjusting said rolls and side edge guides together axially of said rolls.

2. Mechanism of the character claimed in claim 1, in which said web-feeding rolls are journaled 50 about axes arranged in a common plane and geared together to rotate in unison in alternately opposite directions.

3. In mechanism for unwinding mill rolls, the 55 combination with a carriage which is laterally adjustable with respect to the path of a continuous web coming from a mill roll, of a plurality of spaced web-feeding rolls rotatable about parallel transverse axes on said carriage, said web-feeding rolls being geared together to rotate in unison in alternately opposite directions, said web-feeding rolls being constructed and arranged to frictionally engage a web moving alternately over and under said rolls, means for driving said web-feeding rolls to impart a peripheral velocity 60 to said rolls in excess of the linear speed of said web, and lateral edge guides for said continuous web mounted on said carriage.

4. In mechanism for unwinding mill rolls, the 70 combination with stationary laterally spaced supports, of a carriage frame slidably transversely on said stationary laterally spaced supports, said carriage being provided with laterally spaced bearing blocks, a plurality of spaced web- 75

feeding rolls journaled in said bearing blocks about parallel axes arranged in a common plane and geared together to rotate in unison, said web-feeding rolls being constructed and arranged to frictionally engage said web in alternation above and below said common plane, a power-driven shaft rotatably mounted on one of said stationary supports, operating connections between said power-driven shaft and one of said 10 web-feeding rolls for imparting thereto a peripheral velocity to said rolls in excess of the linear speed of said web, and means for laterally adjusting said carriage on said stationary supports.

5. In mechanism for unwinding mill rolls, the combination with a stationary base frame extending longitudinally of the path of a continuous web drawn from a mill roll, of a carriage slidable transversely on said stationary base frame, a plurality of web-feeding rolls rotatable about 15 parallel axes arranged in a common plane, said web-feeding rolls being journaled in said carriage and geared together to rotate in unison in alternately opposite directions, a power-driven shaft journaled in said stationary base frame rotatable 20 about a fixed axis extending longitudinally of the path of said continuous web, operating connections between said power-driven shaft and one of said web-feeding rolls, said web-feeding rolls being 25 constructed and arranged to frictionally engage said web one after another and alternately over and under said rolls, and means for laterally adjusting said carriage on said stationary base.

6. In mechanism of the character described, the combination of means for feeding a continuous web under a substantially constant tension and velocity, a power-driven web-feeding roll having a peripheral velocity in excess of the substantially constant velocity of said web, means 30 for constraining said web to a path of unchanging length extending between said web-feeding roll and said web-feeding means, said web-feeding roll being arranged to have web-feeding engagement with said continuous web for drawing 35 additional web from a source of supply when under a tension in excess of the substantially constant tension under which the web moves over said path of unchanging length.

7. In mechanism of the character described, the combination with means for feeding a continuous web under a substantially constant ten-

sion and velocity, of a power-driven web-feeding roll for drawing additional web from a source of supply and feeding it to said web-feeding means for reducing the tension in the web, means for driving said web-feeding roll at a peripheral velocity in excess of the substantially constant linear velocity of said continuous web, and means for constraining said continuous web to a fixed path of constant length during its movement under substantially constant tension from 10 said power-driven web-feeding roll to said web-feeding means, said web-feeding roll being arranged to have the continuous web drawn into feeding engagement therewith at recurring intervals due to the forward movement imparted 15 to the web by said web-feeding means.

8. In mechanism of the character described, the combination with means for feeding a continuous web from a source of supply at substantially constant velocity, of a web-feeding roll arranged in the path of said continuous web between said source of supply and web-feeding means, said web-feeding roll having a peripheral velocity in excess of the velocity of said web, and means for constraining said continuous web to 20 a path of unchanging length between said web-feeding roll and web-feeding means, said continuous web being drawn into intermittent feeding engagement with said web-feeding roll for 25 maintaining a substantially constant tension in 30 said web.

9. In a machine of the character described, the combination with peripherally-spaced web-feeding rolls rotatable about fixed parallel axes 35 and arranged to frictionally engage alternately opposite surfaces of said web for unwinding the web from a mill roll at recurring intervals of time, web-feeding means for feeding said web at substantially constant velocity past and away from said web-feeding rolls, power connections 40 for driving said web-feeding rolls at a peripheral velocity in excess of said substantially constant velocity of said web, and means for constraining said continuous web to a fixed path between said web-feeding rolls and web-feeding 45 means, said continuous web being tightened into feeding engagement with said web-feeding rolls at recurring intervals for maintaining said web under substantially constant tension.

50
